COATING APPARATUS

Henry E. Van Derhoef, Rochester, N. Y., assignor
to Eastman Kodak Company, Rochester, N. Y.,
a corporation of New Jersey

Application April 13, 1939, Serial No. 267,640

4 Claims. (Cl. 91—51)

This invention relates to coating apparatus and more particularly to coating apparatus for continuously coating sheets or films with various coating solutions.

5 In such coating apparatus it is customary to rotate an applicator roll partially submerged in a hopper containing the coating solution, and the sheet or film to be coated is passed between a guiding roll and the applicator roll so that the sheet or film becomes coated on one side with the coating solution. The coated sheet or film is then conducted through other suitable processes as may be desired.

10 It has been experienced in employing such apparatus that the maintenance of a constant flow of solution to and from the hopper determines to a great extent whether or not the applied coating will be uniform over the expanse of the surface being coated.

15 20 The problem of maintaining a constant supply of coating solution in the coating hopper, as well as the even distribution of the coating solution throughout the hopper has been given considerable study. Various schemes for introducing and removing the coating solution have been devised. These vary from the so-called "flow type" hopper to that known as the "center feed" type hopper. While these devices operate to produce satisfactory coatings, they require more 25 regulation and adjustment for their proper operation than is desirable. With the "flow type" hopper it is rather difficult to provide a constant supply of coating solution to the flow hopper, and with the "center feed" hopper it is difficult 30 to determine the right proportions of openings for a definite distribution of the supply throughout the length of the hopper.

35 Some difficulty has also been experienced in keeping the composition of the bath within proper limits and to remove foreign matter, which may from time to time enter the bath from various sources, while the coating apparatus is in operation.

40 45 An object of the present invention is, therefore, an improved coating apparatus in which the coating solution is uniformly distributed to the coating hopper and to the applicator roll at the regular rate.

Another object of the invention is an improved 50 coating apparatus in which the coating solution may be uniformly removed from the coating hopper in proportion to the rate at which it is introduced into the hopper.

In accordance with one feature of the invention these and other objects are attained by em-

ploying a coating apparatus in which the coating solution is introduced into the coating hopper by a fluted or toothed roller which extends parallel to the applicator roll and rotates at regular intervals in a supply hopper containing a supply of the coating solution. The rotation of the toothed roller transfers, by means of its teeth and grooves therebetween, uniform amounts of solution all along the length of the coating hopper at a position parallel to and equidistant from the applicator roll. Preferably the toothed roller is substantially the same length as the applicator roll.

5 10 15 In accordance with another feature of the invention a similar fluted or toothed roller may be positioned also adjacent and parallel to the applicator roll on the opposite side from the first roller, in an outflow hopper and may be caused to rotate at regular intervals to remove the coating solution from the coating hopper.

20 25 30 The present invention is particularly adapted for use in the manufacture of photographic film. In his art a film base or support is first formed and this support is then coated with a suitable subbing layer prior to the application of a light sensitive emulsion.

35 40 45 Certain of the undesirable coating methods heretofore employed for this purpose produce longitudinal lines running along the length of the support to which the subbing solution is being applied. These may be caused by non-uniform mixing of the fresh subbing solution with the solution already in the coating hopper as well as caused by uneven flow lines on the surface of the solution. Also in certain coating apparatus of the prior art there are "dead" areas in which particles of the film base may collect and where the solution may be of a different concentration or composition than at other portions of the hopper. Such undesirable factors cause irregularities and imperfections in the resulting photographic film.

50 My method of introducing and removing the coating solution by toothed rolls eliminates such undesirable features and results in uniform coatings on film base or other such supports.

The invention will be more clearly understood by reference to the following detailed description and drawing in which:

Fig. 1 is an end elevation view in section of my improved coating apparatus;

Fig. 2 is an elevation view of a side section taken on line 2—2 of Fig. 1;

Fig. 3 is an enlarged end sectional view taken on line 3—3 Fig. 2 showing the toothed roller

and supply hopper positioned adjacent the applicator roll; and

Fig. 4 is a view in section showing the toothed roller and outflow hopper for removing the solution from the coating hopper.

Referring to Figs. 1 and 2 there is shown a coating apparatus comprising a base 5, a coating hopper 6, an applicator roll 7 and a guide roll 8 around which a portion of a continuous 10 strip of material to be coated is shown at 9. The guide roll 8 may be suitably mounted and rotated by apparatus not shown.

The supply hopper is shown at 11 having a concave portion 12 extending longitudinally thereof.

15 In the concave portion 12 of the supply hopper 11, is mounted in rotatable counterclockwise arrangement, a toothed feed roller 13. This toothed feed roller 13, as shown more clearly in Fig. 3 rests on the concave portion 12 of hopper 11 and is rotated 20 around its pintles one of which is shown at 15 engaging slotted block 10 by means of slot 14. Block 10 is removably attached to the wall 16, and when it is desired to remove roller 13 from the supply hopper 12 for the purpose of cleaning and 25 so forth block 10 is first removed permitting free access to the roller. A similar slotted block is positioned at the opposite end of the toothed roller 13.

The toothed roller 13 is turned by the driving 30 mechanism mounted in chamber 17, this chamber being formed by side walls 18 and 19, base 21, top 23 and front and back walls 31 and 32. The driving mechanism comprises a pawl 22 which engages the toothed roller 13 and turns the roller 35 in accordance with the rotation of shaft 24 which motion is transmitted to the pawl 22 through worm 25, worm gear 26, an adjustable pin 30, pivoted lever 27 and stud 28. As shown in Fig. 1 the driving shaft 24 is mounted in suitable bearings in 40 the walls 18 and 19 and, as shown in Fig. 2, the pivoted lever 27 is pivoted on bolt 33 which engages wall 32 and the worm gear 26 is rotatably mounted on shaft 34.

As shown in Figs. 1 and 2 the operation of lever 45 27 depends on the movement of the adjustable pin 30. This pin 30 as shown in Fig. 2 is associated with a slotted member 35 through its attachment with a shoe 36 which is adapted to slide in the slot 37. As worm gear 26 rotates, the pin 50 30 will follow a circular orbit concentric with shaft 34, the diameter of such orbit being variable according to the position in slot 37 in which the shoe 36 is changed by the pin 30. The pin 30 thus will move up and down in slot 20 of lever 27 55 imparting a rocking movement to the latter, and this movement will cause pawl 22 first to engage the toothed roller 13 and rotate it in a counterclockwise direction a fraction of one revolution and then to slip back over the roller and into engaging position. The degree of such fractional 60 rotation may be varied by loosening the clamped shoe 36 and relocating it in a different position in the slot 37.

As will be apparent from Fig. 1 the mechanism 65 for removing coating solution from the coating hopper 6 is quite similar to that above described for introducing the coating solution into the coating hopper.

As in the case of the toothed feed roller 13, the 70 toothed roller 41 is rotatably mounted in the outflow hopper 42 which has a concave portion 43 extending longitudinally thereof. The radius of curvature of the concave section 43 of the hopper 42 and that of the toothed roller 41 are substantially equal and, as shown in Figs. 1 and 4, the

toothed roller 41 rests upon the outflow hopper so that substantially no solution can pass from the coating hopper 6 to outflow hopper 42 without the rotation of the toothed roller 41. The toothed roller 41, as shown in Fig. 4, is rotatably maintained in the outflow hopper 43 by means of slotted block 10 having a slot 14 therein.

The toothed roller 41 is turned by a driving mechanism similar to that described for roller 13, mounted in chamber 44. This chamber is formed 10 by side walls 54 and 55, the end walls 31 and 32, and top wall 23, a portion of which is shown in Fig. 2. The driving mechanism comprises a pawl 46 which engages the toothed roller 41 and turns the roller in accordance with the rotation of shaft 15 47 which motion is transmitted to the pawl 46 through worm 48, worm gear 49, adjustable shoe 50, pin 51, pivoted lever 52 and stud 53. This mechanism operates the same as that for rotating the toothed feed roller 13 and is mounted in a 20 similar manner. It is obvious from the drawing that pawl 46 turns toothed roller 41 by a thrust action while pawl 22 turns toothed roller 13 by a pulling action. It will also be apparent that the teeth of both the toothed rollers 13 and 41 are 25 so shaped that they will provide drainage surfaces when the teeth lift out of the solution thus avoiding the return of the coating solution to either the supply hopper or the coating hopper.

Any suitable motive force for operating the 30 mechanism can be connected to shafts 24 and 47 as will be understood. If desired the temperature of the coating solution may be regulated before it is introduced into the hopper, and the hopper 6 may be suitably heated if desired.

To operate the apparatus coating, solution is permitted to flow through inlet 55 to fill the supply hopper 11. The hopper 6 may be filled from a direct supply pipe, not shown, to a level as is indicated in Figs. 3 and 4. The strip or film base 9 40 to be coated is suitably positioned around guide roll 8, and roll 8 is adjusted by means not shown to permit the film base 9 to contact the periphery of applicator roll 7 which is suitably mounted and rotated by means, not shown, in hopper 6.

The apparatus is now ready for operation and toothed rollers 13 and 41 and the applicator roll 7 and guide roll 8 are caused to rotate. As is indicated in Fig. 1, the toothed roller 13 turns in a counterclockwise direction while the adjacent applicator roll 7 turns in a clockwise direction. It will be evident that this will permit a surface layer of fresh coating solution to continually come in contact with the applicator roll 7 and be carried up into contact with the film 55 base 9.

As previously explained the solution owing to its uniform distribution to the hopper 6, contacts the applicator roll 7 along its whole length very evenly and this eliminates longitudinal 60 stripes in the coated surface. Furthermore this arrangement assures that the solution contacting the film base will be of substantially uniform composition and eliminates "dead" areas in the coating bath.

As will be evident from reference to Figs. 1 and 4 toothed roller 41 turns in counterclockwise direction and this will uniformly remove coating solution from hopper 6 and permit it to flow through drain 56. If foreign matter such as 70 flakes from the film base, or the like, fall into the hopper they will be removed from the surface of the liquid without being mixed into the remainder of the coating solution. Also the portion of the coating solution which may be car- 75

ried over by the applicator roll will normally be carried out through the outflow hopper 42 and drain 56 without the possibility of contaminating the remainder of the solution in the coating hop-
5 per.

It will be understood that the rates of rotation of the applicator and guide rolls and the input and output toothed rolls may be varied as is de-
10 sired. This will depend somewhat on the viscosity 10 of the solution and characteristics of the film.

This apparatus permits the production of a very uniformly coated sheet or film and overcomes many undesirable features of apparatus now commonly employed.

15 What I claim is:

1. In an apparatus for coating films or sheets, a coating hopper adapted to contain a coating solution, an applicator roll positioned to be partially submerged in the solution and adapted to 20 coat the solution onto a film, a feed hopper adapted to contain a supply of coating solution positioned adjacent said coating hopper, and a fluted roller having flutes substantially parallel to the length of the roll rotatably mounted be-
25 tween said hoppers and in contact with said feed hopper solution and adapted to convey solution by means of the flutes from the feed hopper to the coating hopper when rotated in a counterclockwise direction.
- 30 2. In an apparatus for coating films or sheets, a coating hopper adapted to contain coating solution, an applicator roll positioned to be partially submerged in the solution adapted to coat the solution onto a film, a feed hopper adapted to 35 contain a supply of coating solution positioned adjacent said coating hopper, and a fluted roller having flutes substantially parallel to the length of the roller rotatably mounted between said hoppers, and in contact with said solution and
40 parallel to the applicator roll, adapted to convey solution by means of the flutes from the feed hopper to the coating hopper when rotated in a counterclockwise direction.

3. In apparatus for coating films or sheets, a 45 coating hopper adapted to contain a coating solu-

tion, means for maintaining the supply of solution substantially constant, an applicator roll positioned to be partially submerged in the solution adapted to coat the solution onto a film, an output hopper adapted to conduct solution away 5 from said coating hopper, and a fluted roller having flutes substantially parallel to the length of the roll rotatably mounted between said coating hopper and output hopper and in contact with the solution in the coating hopper and mounted 10 parallel with the applicator roll adapted to transfer solution by means of the flutes from the coating hopper to the output hopper when rotated in a counterclockwise direction.

4. In apparatus for coating films or sheets, a 15 coating hopper adapted to contain a coating solution, an applicator roll positioned to be partially submerged in the solution adapted to coat the solution onto a film, a feed hopper adapted to 20 contain a supply of coating solution positioned at one side of said coating hopper, a fluted roller having flutes substantially parallel to the length of the roll rotatably mounted between said hoppers parallel to the applicator roll and of sub-
25 stantially the same length and normally in contact with the solution in the feed hopper adapted to transfer the solution from the feed hopper to the coating hopper by means of its flutes when rotated, an output hopper positioned at the 30 opposite side of the coating hopper adapted to 35 conduct solution away from said coating hopper, and a fluted roller having flutes substantially parallel to the length of the roll rotatably mounted between said coating hopper and output hopper and normally in contact with the solution in the coating hopper and parallel to the applicator roll adapted to transfer solution from the coating hopper to the output hopper by means of its flutes when rotated, and means for rotat-
40 ing said fluted rollers in counterclockwise direc- 40 tion said first mentioned roller adapted to be rotated at a rate sufficient to maintain said solution in said coating hopper at a predetermined level.

HENRY E. VAN DERHOEF. 45
